UNITED STATES PATENT OFFICE.

JOHN A. BIRTCIEL, OF TULSA, OKLAHOMA, ASSIGNOR OF ONE-HALF TO TIDAL OIL COMPANY, A CORPORATION OF OKLAHOMA.

PUMPING JACK.

Application filed December 1, 1924. Serial No. 753,293.

To all whom it may concern:

Be it known that I, JOHN A. BIRTCIEL, a citizen of the United States, residing at Tulsa, in the county of Tulsa and State of 5 Oklahoma, have invented certain new and useful Improvements in a Pumping Jack, of which the following is a specification.

This invention relates to improvements in pumping jacks.

10 The primary object of this invention is the provision of a pumping jack structure, preferably to be used for pumping in connection with oil wells, and including a novel structure by means of which the polish 15 rod may have a true reciprocatory movement, in a straight line, during the pumping operation.

A further object of this invention is the 20 provision of an improved pumping jack by means of which a greater pumping stroke is obtained than is possible with conventional pumping jacks, so that a greater fluid yield is obtained, with a substantial saving in power, and reduction in operating 25 expense.

A further object of this invention is the 30 provision of a novel pumping jack construction, which is relatively simple in operation, and which is operated to give a true vertical reciprocatory movement to the polish rod, thus eliminating much of the wear and tear on the rod, stuffing box, and stuffing box rings, occasioned by conventional pumping jacks, and decreasing the loss of 35 oil from leaking stuffing boxes and the like.

Other objects and advantages of this invention will be apparent during the course 40 of the following detailed description.

In the accompanying drawings, forming 45 a part of this specification, and wherein similar reference characters designate corresponding parts throughout the several views,

Figure 1 is a perspective view of the improved pumping jack, showing novel structural features thereof.

Figure 2 is a side elevation of the improved pumping jack, showing the same in different operating positions, in full and dotted lines, and clearly designating the true vertical reciprocatory movement of the polish rod.

In the drawings, wherein for the purpose of illustration is shown only a pre-

ferred embodiment of the improved pumping jack structure, the letter A may generally designate the improved pumping jack, which may include the conventional triangular shaped rocker frame B; pivotally mounted for rocking upon a foundation or base C. A main beam D is provided, having connection intermediate its ends, by a pitman E, with an end of the rocker frame B. To one side of the pitman 60 E the main beam D has pivotal connection with the polish rod F of the pumping equipment G, and at the opposite side of the pitman E the beam D has pivotal connection with the frame B, by means of a 65 connecting rod structure H and extension K fixedly connected with the frame B. Improved means L is provided for guiding the beam D as it is rocked, to insure a straight line pumping action of the polish 70 rod F, ordinarily in a vertical direction.

Referring to the triangular rocker frame B, the same, in reality is the conventional type of pumping jack used for oil pumping purposes, such as the Oklahoma pattern oil 80 well pumping jack. It comprises the bottom brace or beam 10; upright brace 11; and diagonal brace 12, which are rigidly connected, and may be formed in any approved manner, to provide the triangular jack frame 85 B, as shown. Intermediate its ends the bottom brace 10 is rockably supported, having a saddle piece 14 pivotally mounted upon a bearing plate 15; the latter being supported upon spaced parallel planks 17, 90 mounted on the platform C. As in well known construction the upright brace 11 at its upper end is preferably provided with a stirrup box 18, to which the stirrup 19 is attached, so that the power line or cable 20 95 may be connected with the stirrup 19. The pitman E has a pivotal rest upon a block or plate 21 at the outer end of the bottom brace 10, opposite the pivot mounting of the frame with respect to the upright brace 11.

The main pumping beam D preferably comprises a pair of spaced parallel channels 25 and 26, which at their forward ends are connected by bolts 27. At the forward or outer end of the beam D the polish rod F has 100 a pivotal connection, of any approved character, such as the provision of bearing extensions 30 rigid with the polish rod F, resting on bearing blocks 31 carried by the beam sections 25 and 26. The polish rod F 105 110

thus has a fixed pivot axis connection with the beam D. Intermediate its ends, and closer adjacent the polish rod connected end thereof than the opposite end, the beam D 5 has connection with the pitman E, as at 33. At its end opposite the end to which the polish rod is connected, the beam D is connected to the pumping jack frame B by means of the connecting rod structure H 10 and extension K. The extension K preferably comprises a pair of channel sections 35 and 36, securely bolted, as at 37, at opposite sides of the bottom brace 10 of the frame B, so as to extend outwardly from the upright brace 11, at right angles thereto, and at the opposite side of said upright brace 11 with respect to the pivot mounting of the frame B. The parallel extension sections 35 and 36 at their outer ends are provided 15 with a cross bolt or member 39, which pivotally supports the sections 40 and 41 forming the connecting rod extension structure H. At their upper ends the connecting rod sections 40 and 41 have pivotal connection 20 with the sections 25 and 26 of the main beam A, by means of a bolt 43 transversely arranged through the beam sections 25 and 26.

With respect to the guide structure L, the same is provided in order to secure a proper vertical reciprocation of the polish rod. To 30 this end, it is preferred to provide arcuate guide members 50 and 51, of any approved character, which provide segmental slots 52 and 53 respectively, struck from the same radii. These guide members 50 and 51 are supported at their lower ends by means of standards 54 and 55 respectively, the lower 35 ends of said standards being bolted to the platform or base C, so that the guide members 50 and 51 have the concavities of the slots 52 and 53 facing the pitman and polish rod connections with the beam D. The bolt 43 above mentioned is preferably provided 40 with guide blocks 56, at the outer ends thereof, laterally of the beam sections 25 and 26, which are slidably mounted in the slots 52 and 53 of the guide members 50 and 51. To brace the guide members 50 and 51, so that they are stably disposed at 45 opposite sides of the beam D, with the said beam extending between said guide members at its rear end, it is preferred to connect the guide members 50 and 51 at their upper ends by means of a cross rod 58, and to brace the upper ends of the guide members 50 and 51 by means of diagonally disposed 50 brace rods 59 and 60, connected respectively with the guide members 50 and 51, and extending diagonally downward for connection with the base C, by bolt means 61, at the opposite end of the base C from that end to which the uprights 54 and 55 are connected.

Referring to the operation of the invention, when the power is applied to the frame B, through the line or cable 20, the forward

end of the bottom brace 10 will of course be moved upwardly, moving the pitman E therewith, and rocking the main beam D upwardly, pulling the polish rod F for an up-stroke. The rear end of the beam D is not 70 pivoted on a fixed axis, and is pulled downwardly as the forward end of the beam D moves upwardly, due to the connecting rod construction H, having connection with the extension K. During this upstroke of the 75 polish rod F, the beam D is accurately guided by means of its connection with the guide members 50 and 51, so that the axis of connection of the polish rod F and beam D moves in a straight line, preferably vertical, 80 and in direct alignment with the vertical stroke of the polish rod F. When the forward end of the main beam D is at its extreme upper position, the rear end of said beam, rests in the slots 52 and 53, at the lower ends of the said slots, as is illustrated 85 by the dotted lines in Figure 2 of the drawings. When the power application is released, the weight of the pumping equipment G pulls the beam D downwardly. The connecting rod structure H operates to elevate the rear end of beam D when the other end is lowered. Thus, both ends of the beam D are free, and move in opposite directions, 90 creating a longer stroke than is possible with the old style of pumping jack, and at the same time the polish rod is maintained in perfect alignment; the pull being always directly in line with the pumping polish rod 100 F, and no lateral tendency is exerted on the polish rod, due to the force applied by the pumping jack.

Merely by detachment of the bolt means 61 the lower ends of the braces 59 and 60 may be released from the base C to permit 105 the end-wise movement of the standards 54 and 55 upon their supporting bolts of the base C, whereby the main jack beam D may be folded back to clear the well casing from 110 obstruction during removal of polish rods, sucker rods, tubing, or the like.

An important feature of the pump in comparing the same with conventional pumps, is that the pumping stroke is doubled and 115 at the same time the power necessary to operate the jack is reduced.

Various changes in the shape, size, and arrangement of parts may be made to the form of pumping jack structure herein described, without departing from the spirit 120 of the invention or the scope of the claims.

I claim:

1. In combination a reciprocating polish rod, a base, a beam pivotally supported on the base intermediate its ends, a main beam, a pitman connecting the first mentioned beam at one side of the pivot axis thereof with said main beam intermediate the ends of said main beam, a connecting rod connecting the first mentioned beam with the 125

main beam at the opposite side of the pivot axis of the first mentioned beam with respect to said pitman connection, and means connecting the polish rod with said main beam to the opposite side of the pitman connection with the main beam with respect to said connecting rod connected with said main beam.

2. In combination a reciprocating polish rod, a base, a beam pivotally supported on the base intermediate its ends, a main beam, a pitman connecting the first mentioned beam at one side of the pivot axis thereof with said main beam intermediate the ends of said main beam, a connecting rod connecting the first mentioned beam with the main beam at the opposite side of the pivot axis of the first mentioned beam with respect to said pitman connection, means connecting the polish rod with said main beam to the opposite side of the pitman connection with the main beam with respect to said connecting rod connected with said main beam, and guide means to which said main beam is slidably connected whereby to maintain the main beam in position to exert a pull in a straight line longitudinally of the polish rod.

3. In combination with a reciprocating polish rod, a rocker frame, power means for rocking the frame on a fixed axis, a main beam, connecting rod means pivotally supporting the main beam above said frame in connected relation with the frame to one side of the axis of said frame, a pitman connecting the frame with said main beam at the opposite side of the pivot axis of said frame, means connecting the polish rod with said main beam, an arcuate guide member, and means slidably connecting the main beam with the arcuate guide member whereby to move the main beam longitudinally as the same is rocked by actuation of said frame to maintain a direct straight line pull on said polish rod.

4. In a pumping jack the combination of a base, a beam pivotally mounted intermediate its ends upon said base, power means for rocking said beam, a main beam, a connecting rod pivotally connecting the main beam adjacent an end thereof with the first mentioned beam adjacent an end thereof, a pitman pivotally connecting the main beam adjacent an opposite end thereof with respect to the connecting rod connection therewith to said first mentioned beams adjacent an end thereof to the opposite side of the pivot axis of said first mentioned beam with respect to the connecting rod connection with said first mentioned beam, and a stationary guide member having slidable connection with said main beam whereby to guide longitudinal movement of the main beam as the same is rocked incident to rocking of the first mentioned beam.

5. In a pumping jack the combination of a base, a frame pivotally mounted intermediate its ends on said base, power means for rocking the frame, a beam, rod connections pivotally supporting the beam above said frame and having pivotal connection with the frame at opposite sides of the pivot mounting thereof on said base whereby the beam will be rocked upon rocking of said frame, and guide means for guiding the longitudinal movement of the beam as it is rocked.

6. In a pumping jack the combination of a base, a frame pivotally mounted intermediate its ends on said base, power means for rocking the frame, a beam, rod connections pivotally supporting the beam above said frame and having pivotal connection with the frame at opposite sides of the pivot mounting thereof on said base whereby the beam will be rocked upon rocking of said frame, guide means for guiding the longitudinal movement of the beam as it is rocked, and a polish rod having a pivotal connection with said beam whereby upon rocking of the beam a pull in a straight line will be applied to said polish rod by said beam.

7. In a pumping jack the combination of a supporting base, a frame rockably supported between its ends on said base, a main beam, connecting rod means connecting said main beam with the frame to one side of the pivot axis of said frame, a pitman connecting the main beam with the frame to the opposite side of the pivot axis of said frame, a polish rod, means pivotally connecting the polish rod with the beam, an arcuate member provided with a slot therein, and means slidably connecting the beam in said slot so that upon rocking of the beam by actuation of the frame the beam will be moved longitudinally to exert a pull on said polish rod in a true straight line.

8. In combination with a polish rod and a conventional pivotally mounted pumping jack, an extension fixed on the pumping jack to one side of the pivot axis thereof, a main beam, a connecting rod connecting said extension to said main beam in pivotal manner, and a pitman connected with the conventional pumping jack at a side thereof opposite to the pivot axis thereof with respect to the pivotal connection of the connecting rod therewith, means pivotally supporting the pumping rod on a fixed axis to said main beam, a stationary guide member providing an arcuate slot therein, and means connecting the beam with said arcuate slot so that the main beam upon rocking will be moved slightly longitudinally to always exert a pull on the polish rod in a straight line.

9. A pumping jack structure comprising a base, a frame pivotally supported on the

base between its ends, a power line connected with the frame for rocking the same, a main beam, a pitman connecting the frame at an end thereof with the beam between its ends, a connecting rod structure pivotally connecting the frame at the opposite side of said pivot axis thereof with respect to said pitman pivotally connecting the main beam with said frame, a stationary guide member providing an arcuate slot, and means slidably connecting the beam in said arcuate slot.

10. In combination a supporting base, a triangular shaped frame pivotally supported on said base between its ends, an extension carried by the triangular shaped frame extending to one side of the pivot mounting thereof on said base, a main beam, a pitman connecting the main beam between its ends to an end of said frame, connecting rod means connecting said main beam remote from the pitman connection therewith to the extension of said frame and at the opposite of the pivot mounting of said frame with respect to said pitman connection with the frame, a guide structure fixedly carried by said base providing an arcuate slot, and means slidably in said arcuate slot connecting the main beam to said guide member for movement longitudinally with respect to the frame when the frame is rocked in order to rock said beam.

11. In combination a polish rod, a pivotally mounted power operated frame, a main beam, connecting rods pivotally connected to the frame and to the main beam for supporting the latter in a definite relation to the frame so that it may move bodily towards and away from the frame, means for connecting the polish rod adjacent one end of said main beam, and cam means with which the main beam is associated at the opposite end of the main beam for effecting a longitudinal movement of the beam in order that the polish rod connection with the main beam may have a rectilinear movement during operation of the main beam.

12. In a device of the class described a polish rod, a pivotally mounted power operated frame, a main beam, a plurality of spaced connecting rods pivotally connected with said frame and with said main beam for supporting the main beam from the frame so that the main beam must move with a substantially parallel movement bodily towards or bodily away from the frame, means connecting the polish rod adjacent one end of the beam, a cam, and means connecting the beam at the end opposite the polish rod with said cam to effect a longitudinal movement of the beam as it is rocked by said frame for moving the polish rod connection on the beam in a rectilinear direction.

13. In combination with a polish rod, a pumping jack comprising a base, a rockable power operated beam pivoted on the base, a main jack beam, means pivotally mounting the main jack beam over the first mentioned power operated beam including a pitman connecting the said first mentioned beam and said main jack beam, means providing a bearing on the main jack beam for pivotal connection of the polish rod thereto, guide means to which the main jack beam is slidably connected to offset a rectilinear movement of the bearing axis of the polish rod on the main jack beam during operative movement of the said main jack beam, and a diagonal connecting brace connected at its upper end to said guide means and extending diagonally downwardly towards the base and at its lower end being connected to the base for supporting the guide means in a predetermined relation on said base.

14. In a pumping jack structure the combination with a polish rod, a base, a power operated beam pivotally mounted on said base, a main jack beam, means pivotally connecting the main jack beam over said first mentioned beam including a pitman connected between the first mentioned beam and the main jack beam whereby to cause rocking of the latter upon pivotal movement of the former, means providing a bearing on the main jack beam for the polish rod, a pair of guide frames extending upwardly from said base at each side of the main jack beam, and at their upper ends having cam slots therein at each side of said main jack beam, means carried by the main jack beam slidably extending into said cam slots for guided movement therein whereby to effect a predetermined longitudinal movement of the main jack beam upon rocking of the same.

15. In a pumping jack structure the combination with a polish rod, a base, a power operated beam pivotally mounted on said base, a main jack beam, means pivotally connecting the main jack beam over said first mentioned beam including a pitman connected between the first mentioned beam and the main jack beam whereby to cause rocking of the latter upon pivotal movement of the former, means providing a bearing on the main jack beam for the polish rod, a pair of guide frames connected upon and extending upwardly from said base, at their upper ends having cam slots therein at each side of said jack beam, said main jack beam extending between said guide frames adjacent said slots, means carried by the main jack beam slidably extending into said cam slots for guided movement therein whereby to effect a predetermined longitudinal movement of the main jack beam upon rocking of the same, and diag-

onal brace rods connected at their upper ends to said guide frames and extending diagonally downward for connection at their lower ends to said base at points remote from the connection of the guide frames with said base.

16. In a pumping jack the combination of a polish rod, a supporting base, a power operated beam pivotally mounted on said supporting base, a main jack beam, means pivotally mounting the main jack beam above the first mentioned beam including a pitman connecting the first mentioned beam and main jack beam to insure rocking of the main jack beam upon pivotal movement of the first mentioned beam, means providing a bearing on the main jack beam adjacent an end thereof for said polish rod, guide means supported by the base in up-

wardly extending relation therefrom at the 20 opposite end of the main jack beam from the end thereof to which the polish rod is connected, said guide means having an arcuate guide slot therein alongside of the main jack beam with the concave side of 25 said arcuate guide slot facing towards the polish rod connected end of the main jack beam, and means connected with the main jack beam slidably extending into said arcuate guide slot whereby to effect a longitudinal movement of the main jack beam upon the rocking thereof whereby the bearing axis of the polish rod on the main jack beam will have a perpendicular rectilinear travel during operative movement of the 35 main jack beam.

JOHN A. BIRTCIEL.
